UNITED STATES PATENT OFFICE.

MICHAEL W. MURRAY, OF MILTON, MASSACHUSETTS.

SEPARABLE SCREEN-HINGE.

SPECIFICATION forming part of Letters Patent No. 699,698, dated May 13, 1902.

Application filed August 7, 1901. Serial No. 71,147. (No model.)

To all whom it may concern:

Be it known that I, MICHAEL W. MURRAY, a citizen of the United States, residing at Milton, in the county of Norfolk and State of Massachusetts, have invented an Improvement in Separable Screen-Hinges, of which the following description, in connection with the accompanying drawings, is a specification, like letters on the drawings representing

10 like parts.

My invention is an improvement in hinges for screen-doors and analogous situations, its object being to provide a hinge having a part to be fixed permanently on the door casing or 15 post and a main portion or hinge part proper separable from said permanently-fixed part to be secured to the door in order that the latter may be readily removed for storage in the winter or for any other purpose required.

20 The details of construction of my invention will appear more fully in the course of the following description, reference being had to the accompanying drawings, in which I have shown one embodiment of my invention.

25 In the drawings, Figure 1 is a fragmentary view in front elevation, showing a portion of a screen and the adjacent door-jamb with my invention shown in plan applied thereto. Fig. 2 is an edge elevation of the entire hinge. 30 Fig. 3 is a top plan view of the portion of the hinge which is to be permanently affixed to the door casing or jamb. Fig. 4 is an end elevation thereof.

According to the present embodiment of 35 my invention, the hinge comprises three plate portions A B C, the latter two being provided at their ends with upwardly-projecting ears b c, connected by a pintle d, around which is wrapped a coiled spring s, said spring being 40 preferably coiled reversely from its extended middle portion s', which engages the part C, and the free ends s² of said spring projecting laterally for a purpose presently to be described.

45 The plate B contains adjacent its opposite edges two openings b', and the plate A has two lugs a, provided with overhanging lips or projections a', so that when the plate B is placed over the plate A the lugs a will project through the holes b' and the lips a' will be removed from the surface of the plate B sufficiently to permit the free ends s² of the

springs s to engage beneath them and hold the plates A B snugly in interlocking relatively immovable relation.

55

It will be understood that I do not restrict my invention to the precise details of construction shown, as the interlocking and relatively coöperating parts and construction described may be secured in various modified forms within the spirit and scope of my claims, as set forth hereinafter.

In use the plate C is secured by screws c' or other usual manner to the adjacent edge of a screen-door E, and the plate A is similarly secured to the door post, casing, or jamb P. Then the screen-door, with the attached parts B C of the hinge, is put in place, so that the openings b' inclose the lugs a of the plate A, and the free ends s² of the spring are 70 snapped in place beneath the overhanging lips a', thereby locking the removable part and stationary part of the hinge rigidly in place.

The weight of the door comes on the sides 75 of the lugs A, which may be as heavy and strong for this purpose as may be desired, and the spring ends s² prevent any possibility of the two parts A B getting apart.

When winter comes and it is desired to remove the screen-doors from the house, all that is necessary is to grasp the two ends s³ of the springs between the thumb and forefinger and upon pressing them together pull the door and part B of the hinge away from 85 the part A, thereby instantly removing the door.

Having described my invention, what I claim, and desire to secure by Letters Patent, is—

90

1. A separable hinge comprising a portion adapted to be permanently secured to a stationary part, and a portion adapted to be secured to a movable part, the latter portion comprising a plate to be secured to said movable part, and a plate pivoted thereon, said pivoted plate and said permanent portion having interlocking lugs and apertures to receive said lugs, said lugs filling said apertures, said lugs having overhanging portions 100 a' projecting toward each other, and means for engaging beneath said lugs against the plates having the apertures for holding the separable parts of the hinge together.

95

2. A separable hinge comprising two plates pivoted together and a spring for yieldingly holding said plates apart, one of said plates having means for securing it to a door, and 5 the other of said plates having opposite apertures, combined with a detachable plate provided with lugs adapted to fit said apertures, said lugs having overhanging portions for projecting through said apertures, and 10 said spring having projecting ends adapted

to rest beneath said overhanging portions for locking the two parts together.

In testimony whereof I have signed my name to this specification in the presence of two subscribing witnesses.

MICHAEL W. MURRAY.
